UNITED STATES PATENT OFFICE

HARRY H. WATERS, OF CLINTON, IOWA, ASSIGNOR TO CLIMAX ENGINEERING COMPANY,
OF CLINTON, IOWA, A CORPORATION OF DELAWARE

NEUTRAL BRAKE

Original No. 1,619,449, dated March 1, 1927, Serial No. 60,367, filed October 5, 1925. Application for reissue filed July 24, 1930. Serial No. 470,503.

This invention relates to a neutral locking brake for planetary reversing pulleys, transmission, or hoisting drums; and more particularly to the use of a neutral brake together with suitable linkages whereby ahead, reverse and neutral clutches or brakes are operated under unitary control in properly timed relationship.

It is an object of this invention to provide 10 an improvement in reversing clutch pulleys or cable drums, in which the reverse rotation is secured through planetary gearing of the spur or bevel type by clamping the spider carrying the planetary gears, and the forward motion is obtained by means of a clutch 15 between the live shaft and the pulley or cable drums floating thereon. The improvement comprises a neutral brake for the pulley or cable drum. Such a brake is highly desirable 20 because it would otherwise be highly difficult to maintain a true neutral position between the reverse and forward drums wherein there will be no rotation of the final drive pulley or drum. This is especially 25 true when there is only a light load on the pulley or drum, because of the inherent friction of the planetary gearing which is in motion when the pulley or drum is idle.

It is also an object of this invention to 30 provide a brake on the pulley or drum itself which is actuated by the same lever which operates the forward and reverse clutches thus placing complete control of the mechanism under one lever.

It is a further object of this invention to 35 provide a device of the class described having a self locking arrangement for the brake mechanism adapted to securely lock the transmission or hoist in neutral with the brake engaged.

Other and further important objects of this invention will be apparent from the disclosures in the specification and drawing.

The invention (in a preferred form) is 40 illustrated in the drawing and hereinafter more fully described.

On the drawing:

Figure 1 is a side elevation of a reversing transmission embodying the features of this 45 invention;

Figure 2 is a detailed fragmentary section showing the neutral brake engaging and locking mechanism; and

Figure 3 is a section on the line III-III 55 of Figure 2 showing the interconnected control mechanism for the forward and reverse clutches and neutral brake.

As shown on the drawing:

The planetary reversing mechanism per se is well known so that the gearing has been 60 omitted from the drawing for the sake of clearness. A frame 10 is provided with suitable journals 11 for a live shaft 12 carrying an outboard pulley 13 adapted to be driven by any suitable prime mover. The live shaft 65 carries a clutch 14 shown in the drawing as a shoe clutch having centrifugal weights 15 on the sleeve 16 which is keyed to and slides to the left to contract the shoes 17, the weights being provided to counteract 70 centrifugal action of the shoes and to permit a smooth and gradual decrease in the slip as the clutch picks up the load. The clutch shoes engage on a suitable rim 18 on a drum or pulley 19 which is free on the live shaft. 75 A brake band drum 20 is provided alongside the clutch rim 18 for the neutral brake of this invention. A spider 21 is also freely and separately mounted on the live shaft 80 alongside the pulley drum 19 and carries planetary reversing gearing meshing with suitable gearing within the pulley or drum 19. The periphery of the spider forms a brake drum 22 for the reversing brake band 23, clamping of this brake band while the 85 clutch is disengaged from the pulley 19 serves to drive the pulley in the reverse direction. This above described planetary reversing transmission is well known and is extensively used in marine reverse gears and 90 in various industrial applications, the present invention relating to the use of a neutral brake together with interlocking operating mechanism therefor.

The reversing brake band 23 and the neutral brake band 24 together with the operating mechanism therefor may be exactly identical aside from the interconnecting linkage, so that only a description of the neutral brake mechanism will be given herein. The ends 95 100

of the brake band 24 terminate in sockets 25 through which adjustable pull rods 26 pass, these rods being connected at 27 to levers 28 pivoted at 29 and carrying rollers 30 at their lower ends, said rollers engaging a cam 31 pivoted therebetween. The cam is preferably in the form of an ellipse with small semicircles 32 cut out on the major axis to receive the rollers 30 when the brake 10 is engaged, thus forming a locking engagement therewith which serves to hold the operating mechanism without attention from the operator. The brake band is retracted when, released by means of the springs 33. 15 This operating structure may be conveniently mounted on a cross frame comprising a pair of angles 34 with the pivoted levers 28 mounted therebetween, the cam being pivoted on a block 35 secured between the angles and forming a spacer therefor. It is of course apparent that a toggle operating mechanism of any well known form might be used in connection with the reversing band in lieu of the cam mechanism just described. 20 25 The operating mechanism interconnecting the reverse brake cam 36 with the neutral brake cam 31 and the clutch shifting lever 37 comprises a single lever 38 connected to the arm 39 of a bell crank pivoted at 40 30 by the push and pull rod 41. On the arm 39 intermediate the rod 41 and the pivot of the bell crank, a short connecting rod 42 leads to a crank 43 secured to the reverse brake cam 36, which is operated to engage 35 and lock the reverse brake band by a clockwise motion about its pivot in Figure 3. The tip of the second arm 44 of the bell crank is connected by the link 45 to a crank 46 secured to the neutral brake cam 31. The 40 arm 44 of the bell crank also has a connecting rod 47 pinned thereto intermediate its length and serving to operate the clutch shifting lever 37. The particular point of attachment is so chosen that in the position 45 shown in Figure 3 the clutch is disengaged and a like remark applies to the location of the rod 42 for the reverse brake, the neutral brake being shown in engaged position wherein the rollers 30 on the levers 28 drop 50 back slightly into the recesses provided in the cam. This slight loosening of the brake band does not release the brake for the reason that the coefficient of friction at rest is greater than when there is relative motion 55 between the brake band and the drum so that the slight slackening simply relieves the maximum stress in the brake mechanism without reducing the holding power of the brake below a safe limit. 60 The operation of the unitary control mechanism is through the medium of the lever 38 and rod 41; pulling on the lever moving the rod 41 downwardly in Figure 3 and further rotating the reverse cam counter- 65 clockwise from its already disengaged position as shown in the figure. This same movement releases the neutral brake by rotating the cam 31 and pushes the forward clutch shifting lever into clutch engaging position for direct forward drive of the pulley or 70 drum. The reverse of the above described operation first disengages the direct drive clutch and next applies the neutral brake to bring the drum or pulley to a full stop before engaging the reverse brake by a further 75 movement of the lever 38 which at the same time releases the neutral brake. The neutral brake thus assists very materially in bringing the pulley, and the mechanism driven therefrom, to a quick stop, thus expediting 80 reversal with less strain and wear on the forward clutch and the reverse brake band. 85 The brake mechanism itself affords a greatly simplified structure that is readily adjustable, as both the spring tension for retracting the brake linkage and the brake itself are adjustable to suit the operating conditions. The brake band as a whole is self wrapping and equally efficient in either direction of motion so that little force is 90 required to operate the cam and the notches therein need not be deep to assure a positive lock in brake set position. 95 I am aware that many changes may be made and numerous details of construction may be varied through a wide range without departing from the principles of this invention and I therefore do not purpose limiting the patent granted thereon otherwise than necessitated by the prior art. 100 I claim as my invention: 1. In a device of the class described, a constantly rotating shaft, a pulley rotatably mounted on said shaft, a clutch for coupling said pulley to said shaft, reversing gearing for said pulley, a neutral brake for holding said pulley stationary, and a single operating mechanism interconnecting the clutch, the reversing gearing, and the neutral brake, whereby the application of the neutral brake 105 is automatically performed when reversing the direction of rotation of said pulley. 110 2. In a device of the class described, a constantly rotating shaft, a reversible driven pulley mounted on the shaft, a neutral brake, and operating mechanism therefor interconnected with the pulley reversing mechanism whereby the brake will be applied during a 115 reversing operation. 3. In a device of the class described, a constantly rotating shaft, a reversible pulley mounted on the shaft, forward and reverse driving mechanisms for the pulley, a neutral brake, and means adapted for sequential operation of the mechanisms and brake 120 whereby the brake will be applied during the shift from one mechanism to the other. 125 4. In a device of the class described, a constantly rotating shaft, a pulley freely mounted on the shaft, a clutch for clutching 130

- the pulley to the shaft for rotation therewith, a reversing mechanism extending between the pulley and the shaft for causing the pulley to rotate in a direction reverse to the direction of rotation of the shaft, means for selectively actuating the clutch and the reversing mechanism, said means including a unitary operating lever, a brake for holding the pulley momentarily against rotation during a change in the direction of rotation, and means for operating the neutral brake, said latter named means being responsive to the operation of the means for selectively actuating the clutch and the reversing mechanism.
5. A transmission including a live shaft, a drum thereon, a direct drive clutch between said shaft and drum, a reverse drive for said drum, a brake associated with said drum, means for automatically applying said brake when shifting from one drive to the other and means for automatically locking said brake in the engaged position wherein both drives are disengaged.
6. In a device of the class described a constantly rotating shaft, a pulley rotatably mounted on said shaft, a clutch for coupling said pulley to said shaft, reversing gearing for said pulley, a brake for holding said pulley stationary, a common control for said reversing gearing and said clutch having a reversing position, a clutch operating position, and an intermediate neutral position, and means actuatable by said common control in its neutral position for actuating said brake.
7. A reverse pulley of the character described having, in combination, a drive shaft, a drum loosely mounted on the shaft, means for clutching the drum to the shaft for direct drive, a planetary, reverse mechanism associated with the drum and adapted to drive the drum in a direction opposite to the direction of rotation of the shaft, and a neutral brake associated with the drum, said brake comprising a band arranged to surround the drum, the terminal portions of the band being disposed beneath the drum, followers connected with the terminal portions of the band, and a cam for actuating the followers to cause application of the brake.
8. A reverse pulley of the character described having, in combination, a drive shaft, a drum loosely mounted on the shaft, a clutch mechanism mounted on the shaft for connecting the drum therewith, a reverse mechanism mounted on the shaft for driving the drum in a direction opposite to the direction of rotation of the shaft, and a neutral brake for holding the drum stationary during rotation of the shaft, said brake comprising a drum, a band encircling the drum with the terminal portions of the band located beneath the drum, rocker arms connected to the said terminal portions of the band, and a cam for actuating the rocker arms to cause application of the brake.
9. A reverse pulley of the character described having, in combination, a drive shaft, a drum loosely mounted on the shaft, a clutch mounted on the shaft for connecting the drum therewith, a reverse mechanism mounted on the shaft for driving the drum in a direction opposite to the direction of rotation of the shaft, said clutch and reverse mechanism being adapted for sequential operation, a neutral brake and operating mechanism therefor interconnected with the clutch and reverse mechanism whereby the neutral brake will be applied intermediate the shift from the drive in one direction to the other, said neutral brake comprising a drum, a band encircling the drum, and operating means for actuating the band, said operating means being constructed and arranged normally to support the band clear of the drum.
10. A reverse pulley of the character described having, in combination, a drive shaft, a drum loosely mounted on the shaft, a clutch mounted on the shaft for connecting the drum therewith, a reverse mechanism mounted on the shaft for driving the drum in a direction opposite to the direction of rotation of the shaft, said clutch and reverse mechanism being adapted for sequential operation, a neutral brake and operating mechanism therefor interconnected with the clutch and reverse mechanism whereby the neutral brake will be applied intermediate the shift from the drive in one direction to the other, said neutral brake comprising a drum, a band encircling the drum, and operating means for actuating the band, said operating means being constructed and arranged normally to support the band clear of the drum.
11. A reverse pulley of the character described having, in combination, driven means and driving means, one of said means being adapted loosely to encircle the other of said means, mechanisms for connecting said driving means with said driven means in such a manner that the latter is driven in either a forward or reverse direction of rotation, a control for causing sequential operation of the forward and reverse drive mechanisms, and a neutral brake adapted to hold said driven means against rotation in either direction during the sequential operation of the driving means.
12. A reverse pulley of the character described having, in combination, driven means

and driving means, one of said means being mounted upon and adapted loosely to encircle the other, a first-named mechanism for connecting the said means to cause rotation of the driven means in a forward direction, a second-named mechanism for connecting said means to cause rotation of said driven means in a reverse direction, a unitary control for effecting sequential operation of the forward and reverse drive mechanisms, a brake drum carried by the driven means, a band surrounding said drum, and means for actuating the band to cause operation of the brake whereby the driven means may be held against rotation in either direction during the sequential operation of said forward and reverse drive mechanisms.

13. In a device of the class described, including a driving means within a final driven means, a direct drive and a reversing drive therebetween, a neutral brake adapted to stop the driven means when shifting from one drive to the other and a single operating mechanism interconnecting the direct and reverse driving mechanisms and neutral brake whereby the application of the neutral brake is automatically performed by a shift from one driving means to the other.

Signed at Clinton, Iowa, this 12th day of July, 1930.
